UNITED STATES PATENT OFFICE.

JOHN W. BLODGETT, OF CHICAGO, ILLINOIS.

BUTTON-HOLE ATTACHMENT FOR SEWING-MACHINES.

SPECIFICATION forming part of Letters Patent No. 279,320, dated June 12, 1883.

Application filed September 12, 1881. (Model.)

To all whom it may concern:

Be it known that I, JOHN W. BLODGETT, residing at Chicago, in the county of Cook and State of Illinois, and a citizen of the United States, have invented new and useful Improvements in Button-Hole Attachments for Sewing-Machines, of which the following is a full description, reference being had to the accompanying drawings, in which—

10 Figure 1 is a front side elevation, showing the devices constituting the button-hole attachment attached to a Wheeler & Wilson No. 7 sewing-machine; Fig. 2, a detail of the supporting bracket or arm and a portion of the bed-plate in side elevation, showing the opposite side to that shown in Fig. 1, with the devices forming the button-hole attachment in position; Fig. 3, a detail, being a top or plan view of the feed-ratchet, its operating-lever, 20 check-pawl, and head for attaching the parts to the presser-foot bar; Fig. 4, a detail, being a front end elevation, showing the button-hole attachment in position on the machine; Fig. 5, a detail, being a top or plan view of the head or clamp for attachment of the feed-lever, vibrating cam, and device for operating the lever or cam; Fig. 6, a detail, being a side elevation, partly broken off, of the head or clamp shown in Fig. 5; Figs. 7 and 8, details, being a 25 side elevation and a top or plan view, respectively, of the stop for limiting the throw of the vibrating cam; Fig. 9, a detail, being a side elevation of the needle-clamp shank or support; Fig. 10, a detail, being a top or plan view of the needle-clamp shank or support; Figs. 11 and 30 12, details, being a side and front elevation, respectively, of the needle-clamp with the needle therein. Fig. 12^a is a section taken on line *xx*; Fig. 11; Fig. 13, a detail, being a side elevation 35 of the vibrating cam, with the body thereof partly in section; Fig. 14, a detail, being a front elevation of the vibrating cam; Figs. 15 and 16, details of the journal or pivot in which the vibrating cam is mounted; Fig. 17, a detail, being 40 a front side elevation, showing the operating devices for the feed; Fig. 18, a detail showing the head or support, the vibrating cam, and the spring for keeping the cam properly centered; Fig. 19, a detail, being a top or plan view of the 45 cloth clamping and carrying device; Fig. 20, a detail, being a top or plan view of the bed-plate of the cloth-clamp; Fig. 21, a detail, being a top

or plan view of the horizontal reciprocating plate of the cloth-clamp; Fig. 22, a detail enlarged, being a top or plan view of the upper 55 plate of the cloth-clamp with the feed-rack thereon; Fig. 23, a vertical longitudinal section on line *xx* of Fig. 22, showing the upper plate of the cloth-clamp, the clamp-lever, and the cloth-holding plate; Fig. 24, a vertical longitudinal section on line *yy* of Fig. 22, showing the upper plate of the cloth-clamp, the rack-head and rack, the adjusting-bar, and the guide-plate for working different lengths of button-holes; Fig. 25, a vertical cross-section on line *zz* 65 of Fig. 22, showing the upper plate of the cloth-clamp, the holding-plate, the rack-head for the rack, the adjusting-plate, and the clamping-lever.

This invention relates to devices which are 70 to be attached to a sewing-machine and operated therefrom for the purpose of working button-holes on the machine, and has for its object to construct an attachment for the purpose designated, the parts composing which 75 shall be simple in construction, positive and reliable in action, and easily operated, and have the operation of such nature that it will be automatic after the material has been placed in position, requiring no attention from the operator during the operation of working the button-hole, the devices which carry the cloth being also self-acting in giving the cloth the proper line of travel, and the devices for throwing the needle to cast the thread being also self-80 acting, and the two sets of devices coacting 85 with each other to produce the required movements for working the button-hole. This I accomplish by the mechanism illustrated in the accompanying drawings, and hereinafter 90 described and claimed.

In the drawings, A represents the main head or support of the attachment; A', the depending post or arm for attachment of the vibrating cam; A'', the post or arm for attachment of 95 the return-spring for the feed-lever; A³, the side arm or support for attachment of the vibrating cam-spring; A⁴, the opening for the reception of the head of the machine; B, the shank or tongue which receives and supports 100 the needle-clamp; B', the head or collar by which the shank is attached to the needle-bar; C C', the sliding needle-clamp; C'', the needle; D, the vibrating switch or cam; E, the stop

for the vibrating cam; F, the pin supporting the spring for the vibrating cam; F', the set-nut for holding the pin F; G, the vibrating-cam spring; H, the return-spring for the feed-lever; I I' I'', the feed-lever; J J'', the lever for the feed-pawl; J'', the opening for the connection of the feed-lever with the pawl-lever; K, the feed-wheel; L, the arm carrying the check-pawl; M, the secondary head for attaching the feed wheel and devices to the presser-foot bar; N, the base-plate of the cloth clamping and carrying device; O, the transverse reciprocating plate of the cloth clamping and carrying device; P, the horizontal reciprocating plate of the cloth clamping and carrying device; Q, the cloth-gripping plate; Q', the secondary plates of the cloth-gripping plate; R R', the clamping-lever; R'', the post or standard supporting the lever; S S', the arm or support for the rack; T T', the side racks; T', the movable bar carrying an end rack; T'', the stationary plate carrying an end rack; U, the guide-plate; V, the needle-bar; V'', the arm for operating the needle-bar; V'', the slip-collar for adjusting the needle-bar 25 in relation to its operating arm or lever V'; W, the presser-foot bar; X X', the head of the machine, carrying the presser-foot and needle-bar; Y Y', the bracket or arm supporting the head X X'; Z, the bed-plate of the machine; a, the turned ends of the side pieces of the head or support A; a', the set-screw for securing the head A to the head X' of the machine; a'', the groove at the upper end of the post A'' for attachment of the spring H; a'', the slot in the arm 30 A'' for adjusting the pin F; b, the plate or flange on the end of the shank B; b', the opening between b and the head or socket B' for the needle-clamp; c, the tongue or guide on the needle-clamp; c', the set-screw for attachment of the head or socket; d, the acting portion of the vibrating cam; d', the anti-friction roller; d'', the opening for the pin or journal of the cam; e, the end of the stop against which the cam strikes; e', the slot for 35 adjusting the position of the cam-stop; e'', the opening for the passage of the feed-regulating screw; f, the slot for the pin F to receive the end of the spring G; f', the neck of the pin which enters the slot a'; g, the bar or arm portion of the spring G; g', the coil of the spring G; h, the screw-threaded shank or body of the journal or pivot for the vibrating cam; h', the collar on the journal or pivot; h'', the end of the journal or pivot on which the cam is 40 mounted; h'', the washer for taking up the space in the form of construction shown between the face of the cam and the face of the support A'; i, the end of the arm I of the feed-lever which enters the slot in the pawl-lever; i', the pivot of the feed-lever; i'', the feed-regulating screw; j, the feed-pawl; j', the pin or pivot of the feed-pawl; j'', the spring for the feed-pawl; k, the pinion which drives the rack; k', the guide or center pin for keeping the pin 45 ion in mesh; l, the check-pawl; l', the check-pawl pivot or pin; l'', the check-pawl spring; m, the feed-wheel pin or journal; m', the set-screw for keeping the journal m in position and allowing it to revolve freely; m'', the pin or lock for securing the head M to the presser-foot bar; n, the stationary guides on the plate N; n', the removable guides on the plate N; n'', the studs or pins for the guides n'; n'', the clamping-nuts for holding the guides n' in place; o, the stationary guides on the plate O; o', the removable guides on the plate O; o'', the studs or pins for the guides o'; o'', the clamping-nuts for the guides o'; p, the slot in the movable end rack for adjusting such rack; p', the set-screw for locking the end rack in 50 position when adjusted; q, the set-screw for attaching the plate Q to the plate P; q', the elongated slot in the plate Q; q'', the serrations or teeth in the secondary plates Q'; r, the stop-face of the lever R R', against which the plate Q bears when not in use; r', the end of the lever R R', for forcing the plate Q down and holding it firmly; r'', the pin or pivot of the lever R R'; s, the vertical slot in the head or arm S for the insertion of the guide-plate U; t, t', and t'', the cogs or leaves on the rack T T' T''; u u', the guide portions of the plate U. 55

The head A may be made of steel or other suitable material which can be cast or otherwise formed into shape to have a body, with an opening, A', to receive the head of the machine, the body being formed of a side piece and two end pieces, with turned-in ends a, to leave an opening for the passage of the needle and presser-foot bars in slipping the support onto the head in the form of construction shown. This head, when in position, is clamped and securely held by a set-screw, a', by means of which the ends a are drawn firmly against the face of the sewing-machine head. On the body 60 A of this head, and extending upward, is located a post or standard, A'', the upper end of which, as shown, is provided with a groove, a'', in which is hooked the upper end of the coil-spring H. This post or standard A'' may 65 be cast or formed with the support A, or may be an independent piece, suitably secured thereto. On the under face of the support A, and extending down therefrom is, located another post or standard, A', the lower end of which is provided with a slot, as shown in Fig. 6. This post or standard A' may be formed with the head A, or may be an independent piece suitably secured thereto. Extending out from the body of the support A is an arm or extension, A'', having at its outer end a slot, a''. 70

The shank B and collar B' may be made of cast-steel or other suitable material, and may be formed of separate pieces or of a single piece, the end of the shank having a plate or flange, b, secured thereto or formed thereon, so as to leave a space, b', between it and the collar B', and the collar having a suitable opening to receive the needle-bar, to which it is attached by means of a set-screw, c', or in some 75 other suitable manner. 80

The needle-clamp is located on the shank B, and is formed in two sections or parts, one of which, C', has a suitable opening to receive 85

the shank of the needle C'', which is held therein by means of a set-screw, as usual, and the other portion, C, is provided at or near its center with a vertical flange or guide, c, as shown in Figs. 10, 11, and 12. The sections or parts C C' of this needle-clamp are secured together by means of screws or otherwise, and their adjacent faces are provided with openings, which form an elongated slot to receive the shank B and allow the clamp to reciprocate on such shank. (See Fig. 12a.) In use the head or collar B' is attached to the needle-bar, suspending the needle and holding it in position to pass through the opening in the bed-plate of the machine, as usual, the opening for the passage of the needle being in the form of an elongated slot to allow the needle to pass in the different positions in which it stands by the throw of the clamp.

20 The vibrating switch or cam D is formed from a piece of steel or other suitable material, and has on its acting face a triangular or sharp V-shaped portion, d, by means of which the cam is turned or swung on its pivot to occupy different vertical planes through the action of the flange or guide c. This cam D is provided with an opening, d'', to receive a pin or pivot, h'', by means of which it is journalled or pivoted so as to swing or turn freely. This cam

25 D is located on the inner face of the standard or post A', and, as shown, the body or stem h of its journal or pivot h'' passes through the elongated slot in the lower end of the standard or post A', and is screw-threaded to receive a nut, by means of which it is clamped and held firmly in position, and, as shown, a collar, h', and a washer, h³, are provided, the collar forming a base against which the face of the cam bears, and the washer being for the

30 purpose of taking up the space between the collar and the face of the arm A', so as to bring the cam in proper relation with the flange or guide c, and the cam can be adjusted transversely to have its inclined or acting portion d properly centered to coact with the guide or flange c through the elongated slot which receives the stem h.

The washer h³ is not necessary, as the collar can be made of sufficient width to bring the cam in position. This cam D is pivoted midway of its ends, and is so located and arranged in relation to the rib or flange c on the needle-clamp as that such rib or guide will pass alternately on opposite sides of the acting portion d, such movement being produced by the action of the rib or guide itself, which, in its upward movement, strikes on one of the inclined faces of d and carries the cam over, and at the same time the action of the inclined face and the guide c will carry the clamp also over, so that on the descent of the needle the guide will pass downward without disturbing the cam, but on the upstroke will engage the opposite inclined face of d and throw the cam in the opposite direction, and with it the needle-clamp, which movements will continue with each alternate stroke of the needle-bar,

thereby giving the needle a reciprocating movement, which movement casts the thread to overwork the edge of the button-hole.

In the upper end of the cam D is suitably journalled or pivoted an anti-friction roller or wheel, d', against the face of which the end of the spring-arm g of the spring G bears, which spring G is located on a pin or stud, F, having a square-shouldered portion, f', which enters the slot a'' in the arm A'', and the stud or pin F is locked and held in adjustment by means of a set nut or head, F', the neck or lower end of the pin being screw-threaded to receive the nut or head. I have just stated that the neck or lower end of this pin passes through the slot a'', that is formed in the bar A'', and that on said end of the pin is fitted a nut, F'. Now, it will be evident that by means of this arrangement of parts the nut can be loosened and the pin moved along the slot, and the nut then tightened up against the bar A''. By this means the pin can be adjusted and held in position as required.

The body or coiled portion g' of the spring is located on the stud or pin F, and is prevented from turning by having its end inserted in a slot or opening, f, in the pin, or in any other suitable manner.

The object of the spring G is to prevent the cam D, through the spring action of the arm g, from becoming centered and remaining on its center after the passage of the rib or guide c, the end of the spring-arm g being so arranged and bearing in such manner as to throw the cam over after it has passed the center; and in order to insure this result the pin F is made adjustable, so that by moving it in or out the end of the arm g can be made to bear properly on the anti-friction roller d to keep the cam off its center. By pivoting the cam between its ends it will be seen that when turned in either direction, so as to be off its center, it will be reversed accordingly, by which means the flange or rib c in the ascending and descending movements of the needle-bar throws the cam off from its center.

The swing of the vibrating cam G is limited by a stop, e, formed by the end of the bent or curved portion of the piece E, the body of which is provided with a slot, e', (shown in Fig. 7,) to receive the shank or stem h of the cam pivot or journal, by means of which the piece E is attached to the lower end of the post or standard A', the slot e' being for the purpose of adjusting the stop or end e in proper relation to the cam D for the length of swing. This piece E has a screw-threaded opening, e'', for the passage of the set-screw i'', which opening is so located as to bring the end of the set-screw in line with the feed-lever. Other forms of stops than that shown can be used to limit the throw of the vibrating cam.

The spring H may be made of coiled wire or other suitable material, and its upper end is hooked or otherwise attached to the post or standard A'', and its lower end is hooked or otherwise attached to a short arm or side piece,

I, of the feed-lever, and this spring is for the purpose of returning the lever on the descent of the needle-bar and bringing it in position to be again acted on at the ascent of such bar.

5 The feed-lever is formed of two arms or portions, I I', standing at an angle to each other, and pivoted at or near the center of their juncture by a pin or screw, i', to the face of the post or standard A', the arm I", to which the spring H is connected, extending beyond the pivot a sufficient distance for the spring to act and to return the lever. The arm or portion I of this lever extends downward, and its lower end, i, is made smaller than the other 15 part and enters a slot, J", in the end of the pawl-lever J. The other arm, I', extends out horizontally, and is located and arranged so as to come in contact or be engaged by the collar B, which has a groove or opening, in which the arm rests to prevent it from slipping while being raised by the action of the needle-bar.

The feed-lever J is formed as shown in Fig. 3, and its body or main portion is provided with a slot, J", to receive the end i of the feed-lever, and its secondary portion J' projects beyond the periphery of the feed-wheel, and has attached thereto a feed-pawl, j, which pawl has its acting face formed on a curve corresponding to the circle of the feed-wheel, and 30 provided with serrations or grooves to engage the serrations or grooves on the periphery of the feed-wheel. This pawl j is pivoted to a pin or pivot, j', depending from the end J', and located at the proper point to bring the pawl 35 in position for work, and the pawl is held on its pivot by a spring, j", one end of which is connected with the pivot, and the other end is made to engage with the pawl and force its acting face against the periphery of the wheel 40 K in such manner as to cause the pawl to act with the forward movement of the lever and be non-acting on the return movement, so that with each forward movement of the lever the wheel K will be advanced a distance corresponding to the throw of the lever, which 45 distance coincides with the feed of the machine in making the stitch.

The wheel K has at its center and extending upward a journal or pivot, m, and its periphery is serrated or notched to form a rough surface. At the center of this wheel, on its under side, and formed thereon or suitably secured thereto, is a pinion, k, from the center of which extends down a stud or pin, k'. This 50 wheel is supported by a head or support, M, having an opening for the passage of the presser-foot bar, to which bar it is attached, as shown, so as to be rigid, by a pin, m", which passes through the head and the needle-bar, 55 as shown in Fig. 4. The journal or pin for the wheel K is held in position, as shown, so as to revolve by means of a set-screw, m', the end of which enters a groove formed in the journal or pivot m, and the shank or body of which passes 60 through a screw-threaded opening formed therefor in the head M. This pin, journal, or pivot m also forms a pivot for the lever J,

which lever is located above the wheel K and between it and the face of an arm, L, and the head M, the lever J being curved or bent so 70 as to bring the body or main portion in proper relation with the feed-lever and its end J' in proper position for the pawl j to act on the periphery of the wheel.

The arm or plate L may be formed with the 75 head M, or may be an independent piece firmly secured thereto. This arm extends out from the head, and to its outer end is secured a pawl, l, pivoted onto a pin or pivot, l', and held in position by a spring, l". This pawl l 80 and its pivot l' and spring l" are similar in construction and arrangement to the pawl j, its pivot j', and spring j", and is for the purpose of acting as a check to prevent the wheel K from being returned on the return movement 85 of the lever J, which might happen in some cases if this check-pawl were not provided.

The base-plate N, transverse reciprocating plate O, and horizontal reciprocating plate P may each be made of sheet-steel or other suitable material which can be cut or formed into the desired shape. The base-plate N is to have a body or main portion of sufficient dimensions to furnish a support for the transverse reciprocating plate O, and is to be so formed 95 as to be attached to the bed-plate of the machine by set-screws or otherwise, so as to be held firmly. On the upper face of the body of this plate N are located guides or ears n n', the guides n being stationary and secured in 100 place by rivets or otherwise, and the guides n' being removable and being held in place by means of a jam or set nut, n", which screws onto the end of the stud n", on which the guides are located, the studs being secured to the plate 105 N. These guides or ears n n' are located on the plate N, so as to form clamps to hold the plate O in position and allow it to reciprocate transversely of the machine, the edges of the plate O coming beneath the edges of the 110 guides or ears n n'.

As shown, the plate N has two arms or extensions, each provided with an opening for the passage of a set-screw, by means of which the plate is attached to the bed-plate of the 115 form of sewing-machine shown.

The plate O has a main body of sufficient dimensions to furnish a support for the plate P, with end extensions, O', which come beneath and between the ears n n', the body of the 120 plate being shorter longitudinally than the distance between the ears, so as to permit of the movement of the plate O. In the upper face of this plate O are ears o o', similar in construction and arrangement to the ears n n', the ears o being stationary and the ears o' removable, and held in place on their studs o" by a jam or set nut, o". These ears or guides 125 o' are located at the proper distance apart for the plate P, so that the edge of the plate 130 will come beneath the edge of the ears or guides and be held in place, so as to be free to reciprocate longitudinally of the machine. The plate P has its rear portion correspond-

ing in width to the width of the plates between the ears o o' , and its front portion, as shown, is somewhat wider and extends forward of the plate N , and its forward end is 5 provided with a longitudinal slot in line with the needle when the plates are in position on the machine.

The plate Q may be made of spring-steel or other suitable material, and is attached at its 10 rear end, by a set-screw, q , or otherwise, to the rear end of the plate P , and its front end is provided with an elongated slot, q' , corresponding and coinciding with the slot in the plate P , and extending down through this slot 15 are the serrated edges q'' of the secondary plates Q' , which plates are attached, one on each side of the slot, in any suitable manner, to the face of the plate Q . This plate Q , with the secondary plates Q' and their serrated edges q'' , furnishes 20 a means for clamping and securely holding the cloth with the button-hole slit in line with the center of the elongated slot q' , the teeth or serrations, when the plate Q is forced down, entering the material and catching and holding 25 it in a firm manner. The plate Q is returned by its own elasticity, and is forced or held down by the lever R R' , which lever is pivoted by means of a pin or pivot, r'' , to a post or upright, R'' , attached to the plate P and extending 30 up through a suitable opening above the plate Q . The head R' of this lever has a face, r , against which the plate Q strikes when raised, and this head R' has an arm or extension, r' , having an inclined face, which, when the arm R 35 of the lever is raised, comes in contact with the plate Q and forces such plate down and holds it when down, and at the same time furnishes the means for forcing the serrations or teeth q'' into the material.

40 The head or support for the rack has its inner portion, S' , secured in any suitable manner to the face of the plate P , and its outer portion, S , stands on a higher plane than the inner portion, and furnishes the support proper 45 for the rack. This outer portion is provided with a vertical slit, s , extending from its outer end inward, in which slit is located and secured a plate, U , formed as shown in Fig. 24, having its two sides, u and u' , of different lengths, 50 and these sides form a guide, against which the pin k' bears to hold the pinion k in mesh with the rack. A number of these plates are to be provided, having sides or edges u u' of varying lengths, so as to furnish a guide for the pin 55 corresponding in length to the length of the button-hole slit, and these plates are removably secured in the slot s , so that one can be taken out and other inserted of a proper length of guide for the button-hole slit.

60 On the upper face of the portion S are secured in any suitable manner the side racks, T , the cogs or leaves t of which correspond with the leaves of the pinion k , so as to mesh therewith, the racks being located so as to 65 leave a space between them of greater width than the diameter of the pinion k , so that the pinion will be engaged with but one side rack

at the same time. At each end of these side racks, T , are located end racks, one of which T' , is formed by cogs or leaves t' on the end 70 of a plate, which plate is suitably secured, so as to be stationary, to the face of the bar S , and the other, T' , is formed by cogs or leaves t' on the end of a plate or bar, which bar is provided with an elongated slot, p , for the passage 75 of a set-screw, p' , by means of which the plate is attached to the bar S . This plate or rack T' is adjustable through the slot p , so that the cogs or leaves t' can be advanced or receded to give the pinion a length of travel corresponding to the length of the button-hole slit. The pinion k travels down on one of the side racks, thence across an end rack, back and up the other side rack, and across the other end rack to the starting-point, or vice versa; and 80 no matter at what point on the rack the pinion may start, it will have the proper travel around the racks to give the required movement for working the button-hole slit, the movement of the pinion on the side racks 85 giving a longitudinal travel to the material through the longitudinal reciprocating movement of the plate P , and the travel of the pinion across the end racks giving a transverse travel to the material at the end of the button-hole slit through the transverse reciprocating movement of the plate O . The pinion k is rotated from the feed-wheel K through the pawl-lever J and the feed-lever I I' , and this rotation of the pinion, through its engagement 90 with the side racks, T , imparts a reciprocating movement to the plate P , to which the racks are attached, through the bar or support S S' , and the rotation of the pinion in passing across the end racks gives a transverse reciprocating 95 movement to the plate O through the connection of the plate P therewith.

The parts represented by the letters V , V' , V'' , W , X , X' , Y , Y' , and Z are of the usual forms of construction, as shown, of a Wheeler 110 & Wilson No. 7 sewing-machine; but these parts may be of any of the usual and well-known forms of construction and arrangement in other machines, the head A being formed to adapt it to be attached to the head of the machine with which it is to be used.

In operation the cloth is inserted between the plates P and Q , at the outer end thereof, with the button-hole longitudinally in line with the center of the slot q in the plate Q , and the slot in the plate P , which slots are in line with the needle-opening in the bed of the machine and with the movement of the needle. The plate Q is then forced down by raising the arm R of the lever, forcing 120 the serrations or teeth q'' into the material on each side of the slit. The machine is then started, and at each descent of the needle-bar the stitch will be made, as usual. As the needle-bar descends the material will remain stationary, the several devices being non-acting; but on the ascent of the needle-bar the material will be advanced the required length of feed for the stitch, the several devices coact- 125 130

ing to produce this result. As the needle-bar descends the arm I' of the feed-lever is thrown down by the action of the spring H, throwing the arm I outward, and with it the lever J, 5 but imparting no movement to the feed-wheel K, the pawl j simply sliding on the periphery of the wheel in this movement, and the wheel being held stationary by the check-pawl l, as before described, causing no movement of the 10 plates O P, and in this descending movement the guide or rib c will pass down one of the inclined faces of d until it leaves the end of the cam, when the action of the spring-arm g will throw the cam over and bring the oppo- 15 site inclined face of d in position to be engaged by the face or side of c on the ascent of the needle-bar, and on such ascent the engagement of c with such inclined face will crowd or force the needle-clamp over the limit of its 20 movement, and on the next descent of the needle-bar the rib or flange c will pass down the incline of d with which it was engaged on its ascent until it passes the end of the cam D, when the spring or spring-arm g will act to 25 throw the cam into position for the rib or flange c to engage the other or opposite face of d on the ascent of the needle-bar, which engagement will throw or force the needle-clamp back or in the opposite direction, and this al- 30 ternate engaging of the rib or flange c with the opposite faces of d will continue while the machine is operated, such engagement giving the needle-clamp a reciprocating movement to throw or cast the thread and overwork the 35 button-hole. On each ascent of the needle-bar the arm I' will be engaged by the head or collar B', and be raised thereby, carrying the arm I inward, and with it the lever J, causing the pawl j' on the end j' of such lever to impinge on the 40 periphery of the wheel K and rotate such wheel in a forward direction, and this rotation of the wheel K will, through the pinion k and its engagement with the cogs or leaves of the rack T T' T'', move the plates O and P, as be- 45 fore described, and such movements will continue until the entire length of the button-hole slit has been worked. The length of longitudinal movement of the rack is determined by the length of guide on the plate U, such 50 guide holding the pinion, through the pin k', in engagement with the cogs or leaves t until the end of the guide is reached, when the pinion k passes across the end rack and onto the opposite side rack, with which it is held in en- 55 gagement by the engagement with the opposite face of the guide. When the entire length of the button-hole slit has been traversed, the machine is to be stopped, the arm R of the lever thrown down, releasing the material from the 60 holding-plate Q, and allowing it to be withdrawn and again inserted in a position for the next button-hole slit, when the operation just described is repeated.

The length of stroke of the feed-lever is con- 65 trolled by the set-screw i'', the end of which can be made to operate farther in and out, and thereby limit the swing of the feed-lever.

What I claim as new, and desire to secure by Letters Patent, is—

1. The sliding clamp C C', carrying the needle, and provided with a rib or flange, c, and supported on a shank, B, attached to the needle-bar, in combination with the vibrating cam D, pivoted midway of its ends and thereby balanced, and having a V-shaped acting portion, d, the pivot upon which said cam D turns being supported in the lower end of the standard A', and the said cam being also located relatively to the flange c, so that during operation said flange will pass alternately on 80 opposite sides of the acting portion d, whereby the movements of the cam are produced by the direct action of the flange upon its acting portion, substantially as and for the purposes specified. 85

2. The sliding needle-clamp C C', carrying a needle, and provided with a rib or flange, c, and supported by a shank, B, attached to the needle-bar, in combination with the balanced vibrating cam D, having an acting portion, 90 d, spring or spring-arm g, and head or support A, constructed as described, and carrying the cam and feeding device, said cam being pivoted midway of its ends, and being turned by the action of the flange c on opposite sides of 95 its acting portion d, substantially as and for the purposes specified.

3. The sliding needle-clamp C C', carrying the needle, and provided with a flange or rib, c, and supported by a shank, B, attached to 100 the needle-bar, in combination with the vibrating cam D, having an acting portion, d, and provided with an anti-friction roller, d', spring or spring-arm g, and adjustable pin F, for keeping the spring or spring-arm in proper 105 relation to prevent the cam from centering, substantially as and for the purpose specified.

4. The sliding needle-clamp C C', provided with a flange or rib, c, and supported by a shank, B, attached to the needle-bar, in combination with a vibrating cam, D, having an acting portion, d, and provided with an anti-friction roller, d', spring or spring-arm g, adjustable pin F, and head or support A, carrying the cam and the feed-operating devices, 115 substantially as and for the purposes specified.

5. The sliding needle-clamp C C', provided with a flange or rib, c, and supported by a shank, B, attached to the needle-bar, in combination with the vibrating cam D, having an 120 acting portion, d, stop e, adjustable plate E, and head or support A, substantially as and for the purposes specified.

6. The sliding needle-clamp C C', provided with a flange or rib, c, and supported by a 125 shank, B, attached to the needle-bar, in combination with a vibrating cam, D, having an acting portion, d, adjustable stop E e, spring or spring-arm g, anti-friction roller d', adjustable pin F, and head or support A, substan- 130 tially as and for the purposes specified.

7. The combination of the vibratory two-armed feed-lever I I', operated from the needle-bar, and the return-spring H, with the

5 pawl-lever J J', formed with a slot receiving the one arm of the feed-lever, the feed-pawl *j*, pivoted to the said pawl-lever, and the serrated feed-wheel K, for imparting an intermittent rotary movement to the feed-pinion *k*, said members being organized substantially as and for the purposes specified.

8. The feed-lever I I', operated from the needle-bar, pawl-lever J J', carrying the feed-pawl *j*, arm or plate L, carrying the check-pawl *l*, and head or block M, in combination with the feed-wheel K, provided with serrations on its periphery, and having a journal or pivot, *m*, substantially as and for the purposes specified.

9. A head or block, M, adapted to be attached to the presser-foot bar, in combination with a pivot or journal, *m*, of the feed-wheel K, the plate or arm L, carrying a check-pawl, 20 the pawl-lever J J', carrying a feed-pawl, and a mechanism for operating the said pawl-lever, substantially as specified.

10. A feed-wheel, K, provided at its center with a pinion, *k*, and guide-pin *k'*, pawl-lever J J', carrying a feed-pawl, and a mechanism for operating the pawl-lever from the needle-bar, in combination with the rack T T' T'', arm or support S S', and longitudinal reciprocating plate P, and transverse reciprocating plate 30 O, for imparting movement to the plates from the movement of the needle-bar, substantially as and for the purposes specified.

11. The feed-wheel K, having at its center a pinion, *k*, and a guide-pin, *k'*, operated by suitable devices in a forward direction only from the needle-bar, in combination with the rack T T' T'', guide-plate U, having edges *u u'*, arm or support S S', and plates O P, for giving the plates a longitudinal and transverse reciprocating movement and limiting the travel of the pinion on the rack, substantially as and for the purposes specified.

12. The cloth holding and moving devices, consisting of a base-plate, N, transverse reciprocating plate O, supported and guided on said base-plate, the longitudinal reciprocating plate P, supported and guided on plate O, the spring clamping-plate Q, and clamping-lever R R', in combination with the arm or support 45 S S', carrying a rack, T T' T'', and a driving-pinion and wheel operated from the needle-bar for giving the material the required line of travel to work the button-hole slit, substantially as specified.

55 13. The feed-lever I I', operated from the needle-bar, pawl-lever J J', carrying the feed-pawl *j*, arm or plate L, carrying the check-pawl *l*, feed-wheel K, having its periphery provided with serrations, and having at its center 60 a pinion, *k*, and guide-pin *k'*, pivot or journal *m*, and head or block M, adapted to be attached to the presser-foot bar, in combination with the support or arm S S', rack T T' T'', guide-plate U, longitudinal reciprocating plate

P, and transverse reciprocating plate O, base-plate N, and clamp-plate Q, for holding the material and giving it the proper line of travel for working a button-hole, substantially as specified.

14. In a button-hole attachment for sewing-machines, consisting of a base-plate, a transverse reciprocating plate, a longitudinal reciprocating plate, and a clamping-plate for holding the material, and an arm or support carrying a rack operated by a driving-pinion from a feed-wheel having an intermittent rotary motion in a forward direction only from the machine, a guide-plate, U, having sides or edges of varying lengths for limiting the length of travel of the longitudinal plate to coincide 80 with the length of button-hole, substantially as specified.

15. The sliding needle-clamp C C', carrying a needle, and provided with a rib or flange, *c*, and supported by a shank, B, and socket B' 85 from the needle-bar, vibrating cam D, having an acting portion, *d*, anti-friction roller *d'*, spring or spring-arm *g*, stop *e*, and head or support A, in combination with the spring H, feed-lever I I', pawl-lever J J', carrying a feed-pawl, *j*, feed-wheel K, head or support M, arm or support S S', rack T T' T'', and plates O P Q, substantially as and for the purpose specified.

16. The sliding needle-clamp C C', carrying a needle, and provided with a rib or flange, *c*, and supported by a shank, B, and socket B' 95 from the needle, vibrating cam D, having an acting portion, *d*, anti-friction roller *d'*, spring or spring-arm *g*, adjustable pin or stud F, adjustable stop E *e*, set-screw *i''*, and head or support A, in combination with the spring H, feed-lever I I', pawl-lever J J', carrying a pawl *j*, arm or plate L, carrying the pawl *l*, feed-wheel K, provided with a pinion, *k*, and guide-pin *k'*, head M, arm or support S S', rack T T' T'', guide-plate U, and plates O P Q, substantially as and for the purpose specified.

17. The sliding needle-clamp C C' carrying the needle, and provided with a rib or flange, *c*, and supported by the shank B and socket B' 110 from the needle-bar, in combination with the vibrating cam D, having an acting portion, *d*, anti-friction roller *d'*, spring or spring-arm *g*, adjustable pin or stud F, adjustable stop E *e*, set-screw *i''*, and head or support A, 115 in combination with the feed-lever I I', pawl-lever J J', carrying the pawl *j*, feed-wheel K, provided with a pinion, *k*, and guide-pin *k'*, arm or plate L, carrying the pawl *l*, head or block M, base-plate N, and plates O P Q, 120 lever R R', arm or support S S', rack T T' T'', and guide-plate U, substantially as and for the purposes specified.

JOHN W. BLODGETT.
